Leonard Master

Sellars Patent

In Schedule referred to in this Selling Patent & making part of the same containing a description in the words of the said Leonard Master himself of his improvement in Mortise door fastenings.

Said Improvement consist in such a formation & combination of the several parts of door fastenings, not hinging the formed and combined in Mortise door fastenings as result in a Mortise door fastening occupying less than one half the space of such fastenings heretofore made and not having little more than half their thickness and weight and by this diminished thickness & weight extenuating the use of the Mortise door fastenings & thinner or lighter doors than have hitherto been able to receive them and also in not reducing or weakening the Mortise part of thicker doors to the same as the common Mortise fastenings.

This improved Mortise door fastening only requiring a Mortise of about two inches wide, about of the escutcheons being secured to the solid parts of the door above & below the mortise as a weak part while it being strengthened, and the escutcheons do not work loose as when fastened in the thickness of the solid part of the door, said escutcheons being part of said improved door fastening, or formed of plates of sheet iron or other suitable metal each three inches square and are secured to the door one on the inside & one on the outside by four screws or rivets passing through the inside escutcheons & the solid parts of the door above & below the Mortise part securing to, or riveting upon the outer escutcheons.

One of these side escutcheons has a sliding bolt attached to it near the outer edge, which bolt being slid one quarter of an inch towards the centre of the escutcheons takes a slip on match of a smaller escutcheon or plate attached to and running with the spindle of the door handle or knob and renders the door immovable as also when

lock which is connected through the tumblers with the said plates and thus makes the catch bolt answer the purpose of the thumb bolt which in the common thumb fastening is more expensive and may be difficult to move than such sliding knot. The said improved Mortice fastening is formed of a plate of iron or other suitable metals about one inch wide by four inches long bent at one end to a right angle to form a pin through which the catch bolt passes to secure the door to the said fastening. Said catch bolt is formed of a plate of iron about one eighth of an inch thick three & a half inches long & three quarters of an inch wide except for one inch and a half near the spring where it is but half an inch wide for the purpose of getting the door handle in the middle of the lock plate. Said bolt has a hole with not its side or edge about one quarter of an inch square & about one quarter of an inch from the end next the spring to receive the arm of the tumbler also a similar hole on the same edge or side to receive the key bolt when such is added to the said fastening. The said tumbler is formed in part of a circular plate of iron about one inch in diameter and one eighth of an inch thick with an arm projecting one quarter of an inch from the outer edge of the circle which arm takes into the said hole of the said catch bolt, and moves the same. The part of the tumbler has an opening in its centre about half an inch square through which it receives a nut or pivot said nut or pivot being the remaining part of the tumbler, is circular with a flange at the end where it lies in the lock plate and is square at the other end where it passes through and is riveted to the said circular plate or part of said tumbler the lock plate being between and secured by the flange of the nut or pivot on the outside and by the circular plate of the tumbler on the inside.

Said Nut or pivot has also a hole in its center through which the pin of the handle or door is passed. This tumbler by being in two parts is held to the lock plate by a flange instead of being riveted to it and the rivets being on the

humbler & both moving in the same loose and separate from the lock plate as the common humbler does from its ring in one piece, and riveted to the stationary lock plate. The key hole when back is opposed to the door fastening in very small and is secured to the lock plate at right angles with the catch bolt & when moved by the key shecty into the before mentioned notch of said catch bolt which is then immovable and serves the purpose of the common key bolt.

In Catch on the door frame which is usually straight has the angle or inclined plane requisite to force the catch bolt back and renders it unnecessary that the bolt should be any thicker than strength requires through the usual thickness of the catch bolt the door fastenings to nearly half an inch. A thickness sufficient to get an inclined plane of strength and angle sufficient to force said bolt back on closing the door.

The above improvements are applicable to mortise door fastenings secured either by striking or turning door handle.

Said Mortise door fastening may also be made with a top plate or cover which with the rivets or screws to secure it to the bottom or main plate would render the staples which secure the catch bolt to the main plate unnecessary. The humbler also in the latter case might be in one piece & both ends riveted to the top & bottom plates in the common way.

What I claim as my improvement is to add mortise lock or door fastening made of which such a catch is made as to make a continuation of the before described part of said door fastening not hinged or formed and combined in the door fastening as result to a mortise door fastening itself or there are not to weaken the the hinged part of the door like the common mortise fastening and as narrow as to be embraced & strengthened by the catch which is secured by the striking back on said catch being less expensive and more easily & firmly made than the humbler bolt of the common mortise fastening.

And by other improvements said Mortise door fastening as made applicable to thinner doors than door fastenings

422.

have heretofore been used for & do simple in construction and to be applied at a less price than the wire do. fastenings have been heretofore sold for a less number and capable of taking the place of the clamps and increasing fastenings necessary to Charles doors and to the doors of houses of value. I believe and as such being true is a useful improvement.
